(57) CLAIM

The ornamental design for an articulating joint of an awning, as shown and described.

DESCRIPTION

FIG. 1 is an outside view of an articulating joint of an awning having a unique configuration of the present design; FIG. 2 is an inside view of the articulating joint of an awning;

FIG. 3 is a top view of the articulating joint of an awning; and,

FIG. 4 is a bottom view of the articulating joint of an awning.

End views of the articulating joint of an awning are obscured from view and lack ornamentation.
